UNITED STATES PATENT OFFICE

WAYNE A. BALDWIN, OF WATERTOWN, NEW YORK, ASSIGNOR TO THE NEW YORK AIR BRAKE COMPANY, A CORPORATION OF NEW JERSEY

DUST SEPARATOR

Application filed October 9, 1930. Serial No. 487,621.

This invention relates to dust separators, and particularly to that type in which the air is given a whirling motion and then directed centrifugally against one or more vanes which serve to trap the heavier particles and most of the dust, allowing the air to flow on free of this material.

In prior devices of this sort it has been usual to collect the dust in a chamber or pocket from which it was periodically removed. One purpose of the present invention is to discharge the dust continuously from the device.

Another object of the invention is to cause this discharge to occur at a point or points below the intake for air leading to the separator.

Another feature of the invention has to do with the creation of an outward current through the dust discharge openings, or at least the neutralization of such inward flow tendency as is occasioned by the fact that these discharge passages necessarily lead from the interior of the dust separator.

Another feature of the invention relates to the use of a rotary fan motor driven by the air current flowing inward to the separator. This motor performs a double function; it imparts a whirling motion to the air, and it develops a slight amount of surplus energy sufficient to drive a fan which creates an outward flow through the dust discharge passages, or at least neutralizes the tendency toward inward flow.

Preferred embodiments of the invention are illustrated in the accompanying drawing, in which

Figure 1 is a vertical axial section of the complete device, the plane of section being indicated by the line 1—1 in Fig. 2.

Fig. 2 is a horizontal section, the line of section being indicated by the line 2—2 in Fig. 1.

Fig. 3 is an enlarged fragmentary section showing the fan bearing.

Fig. 4 is a section on the line 4—4 of Fig. 1.

Fig. 5 is a section on the line 5—5 of Fig. 1.

Fig. 6 is a view similar to Fig. 5, and indicating a slightly modified construction.

The casing is composed of two main parts

11 and 12 which are connected by a plurality of equally spaced machine screws, one of which appears at 13, the machine screws engaging mating flanges formed on the two body sections in a familiar manner. The member 11 serves as a cap and is provided with a hexagonal boss 14 to receive a wrench. It is mounted on a threaded pipe, such as the suction line of an air compressor, by means of pipe threads 15. It is customarily mounted with its axis vertical as indicated in Fig. 1. Projecting inward from the cap 11 is a flange or skirt 16 concentric with the threaded opening 15 and the flange 16 is connected by three integral lugs or extensions 17 with the upper margin of a flaring conoidal deflector 18 which is likewise coaxial with the threaded opening 15 and coaxial with the cylindrical or body portion of the member 12. The lower end of the member 12 is closed by an approximately hemispherical bottom 19, and the bottom 19 is formed with an upwardly extending flange or skirt 21 which is larger than and encircles the lower portion of the body 12 beneath an overhanging skirt or flange 22.

Air entering the compressor flows upward beneath the skirt 22, downward between the skirt 21 and the body 12, and enters the chamber 23. The space between the body 12 and the upwardly extending skirt 21 is indicated in Fig. 2 by the numeral 24, and it will be observed that the passage does not completely encircle the body 12, but is periodically interrupted to afford dust discharge passages 25.

In the example illustrated, three dust discharge passages are shown dividing the air inlet passage into three sections equal with each other. From examination of Fig. 2 it will be apparent that the effective area offered for dust discharge is rather less than a third of the area offered for air inlet.

Extending upward from the center of the bottom 19 is a boss 26. This has a pivot bearing 27 preferably of hardened non-corrosive steel. Opposed to this is a second pivot bearing 28 formed on the lower end of an adjustable stem 29 which is threaded through the center of the deflector 18. The upper end of the stem 29 is slotted at 31 to receive

a screw driver by which adjustment is made, and when adjustment has been made, it is maintained by means of a lock nut 32.

Mounted in the pivot bearings 27 and 28 is a shaft or pivot 33 of a combined fan motor and air deflector whose blades are indicated by the reference numeral 34.

The ends of the blades are connected by an annular shroud 35, the shroud being cylindrical in contour.

Formed on the inside of the cylindrical portion of the member 12 are vanes 36, one for each dust discharge opening 25. These are inclined or secant with reference to the cylindrical portion of the member 12 and are so positioned that the dirt trapped by them falls directly to a corresponding dust discharge opening 25.

The dust is prevented from entering the chamber 23 by an inwardly extending flange 37 which defines the lower margin of the cylindrical portion of the body 12 and also defines the lower wall of the dust discharge openings 25 (see Fig. 1). The lower margin 25 of the shroud 35 turns within and close to the inner extremity of the flange 37. The upper margin is a substantial distance above the lower ends of the vanes 36.

In the embodiment illustrated, and as clearly shown in Fig. 2, the fan or motor 34 turns counterclockwise. The angular relation of the vanes 36 with reference to the direction of rotation should be noted.

Mounted on the outer periphery of the shroud 35 are a series of blades or vanes 38 which overlie the flange 37 and consequently are at the upper end of the dust discharge opening 25. In the embodiment illustrated in Figs. 1 to 5 inclusive these vanes are shown as plane and radially disposed, in which case they cooperate with passages 25 after the manner of centrifugal blower blades. Their function is, when driven by inflow through the blades 34, to create an outward flow through the passages 25, or at least, to neutralize any tendency toward inward flow.

To increase the air propelling action of the blades 38, it is practicable to give them a spiral form, as indicated at 38^a in Fig. 6. In fact, the form of these blades may be variously modified within the known principles of fan design, to accentuate the dust discharging effect to whatever extent may prove necessary.

The small opening indicated at 39 in Fig. 1 is for the purpose of draining away any moisture which might collect in the chamber 23.

The inward flow through the inlet passages 24 and shroud 35 very greatly exceeds any outflow which could occur through the passages 25. Hence it becomes possible to derive from the motor blades 34 sufficient excess energy to render the blades 38 effective at all operating speeds. It is important that

the relation of the blades 34 to the blades 38 be such that even at low air flow rates, the blades 38 will function to preclude inflow of air through the passages 25, as otherwise the dust would not be effectively discharged, but might even be drawn back into the air current.

In operation, air enters under skirt 22, flows downward through the passages 24 to the chamber 23, and thence upward between the blades 34. The blades 34 are slightly inclined, as is clearly indicated in Fig. 2, so that they rotate at moderate speed and with considerable force. The reaction of the fan upon the entering air produces a moderate whirling motion and the deflector 18 directs the air outwardly against the blades 36 which entrap the dust particles. The air then flows around the upper margin of the deflector 18 to the discharge connection 15. The dust arrested by the blades 36 flows downward along the blades to the discharge opening 25 through which it is discharged. The discharge is assisted in a material degree by the action of the blades 38.

It will be observed that the device is self-cleaning; that the moving parts are of the utmost simplicity; and that the entire casing structure is formed of two relatively simple castings.

I claim:—

1. The combination with a dust separator having an air inlet and a dust discharge opening isolated from said inlet, of motor means arranged to be driven by air flowing into the separator through the inlet; and a fan driven by said motor means located in said casing beyond said motor means, out of the path of normal air flow and operating to resist inflow through said dust discharge opening.

2. The combination with a dust separator having an air inlet and a dust discharge opening isolated from said inlet, of motor means arranged to be driven by air flowing into the separator through the inlet; and a fan driven by said motor means located in said casing beyond said motor means, out of the path of normal air flow and operating to cause outflow through said dust discharge opening.

3. The combination with a dust separator having an air inlet and having at least one dust discharge opening said inlet and said discharge opening being isolated from each other, the total effective area for dust discharge being materially less than the effective area of the inlet, of motor means arranged to be driven by air entering through the inlet; and fan means driven by said motor means, located in said casing beyond said motor means, out of the path of normal air flow and serving to resist inflow through said dust discharge opening.

4. The combination in a dust separator of

5 a body having an air inlet and a dust discharge; a rotary fan motor driven by entering air and serving to impart rotary motion to such air; dust arresting vane means in said body in the path of such rotating air and adapted to deliver dust to said discharge; and fan means operated by said fan motor and serving to assist dust discharge.

10 5. In a dust separator the combination of a body having passages arranged in annular series, alternate and larger passages being for air inlet, the intervening and smaller passages being for dust discharge; a rotary motor having air deflecting propelling vanes, said 15 motor being mounted in said body in the path of inlet air flow; and a series of oppositely acting vanes mounted on said rotary motor and acting to assist outward flow through the discharge passages.

20 6. In a dust separator the combination of a body having passages arranged in annular series, alternate and larger passages being for air inlet, the intervening and smaller passages being for dust discharge; a rotary 25 motor having air deflecting propelling vanes, said motor being mounted in said body in the path of inlet air flow; a series of oppositely acting vanes mounted on said rotary motor and acting to assist outward flow through 30 the discharge passages; a deflector in said body; and a plurality of fixed vanes against which said deflector directs the air, said vanes serving to arrest dust and deliver it to said discharge passages.

35 7. A structure as defined in Claim 5 in which the inlet ends of the air inlet passages are above the discharge ends of the dust discharge passages.

40 8. In a dust separator, the combination of a casing having an air inlet passage leading to the center of the casing and a peripheral dust discharge; a rotary unit mounted in said casing and including motor blades in the path of inflowing air, ejecting fan blades 45 adjacent the peripheral dust discharge; and an annular partition substantially isolating the two sets of blades from each other.

45 9. In a dust separator, the combination of a casing having an air inlet passage leading to the center of the casing and a peripheral dust discharge; a rotary unit mounted in said casing and including motor blades in the path of inflowing air, ejecting fan blades adjacent the peripheral dust discharge; an 55 annular partition substantially isolating the two sets of blades from each other; a deflector arranged to direct substantially radially outward inflowing air leaving said motor blades; and means forming a circular 60 series of dust collecting pockets in the path of air leaving said deflector.

65 10. In a dust separator, the combination of a casing having an air inlet passage leading to the center of the casing and a peripheral dust discharge; a rotary unit mounted

in said casing and including motor blades in the path of inflowing air, ejecting fan blades adjacent the peripheral dust discharge; an annular partition substantially isolating the two sets of blades from each other; a deflector arranged to direct substantially radially outward inflowing air leaving said motor blades; and means forming a circular series of dust collecting pockets in the path of air leaving said deflector, 70 said pockets being open at their lower ends and directly above said ejecting fan blades.

75 11. In a dust separator, the combination of a casing having an air inlet passage leading to the center of the casing, and a peripheral dust discharge; a rotary unit mounted in said casing on a vertical axis, and including motor blades in the path of inflowing air, ejecting fan blades for producing an outward tendency through said discharge and an intervening annulus isolating said blades from each other; means for directing outward inflowing air leaving the motor blades; and a series of inward projecting vanes in said casing, surrounding 80 said directing means and overhanging the ejecting fan blades.

85 In testimony whereof, I have signed my name to this specification.
